WINDOW FRAME AND SCREEN COMBINATIONS
George J. Kleinknecht, Ridgewood, N.J., assignor to
Screens and Fabricated Metals Corp., North Bergen,
N.J., a corporation of New Jersey

Filed Apr. 8, 1963, Ser. No. 271,228

3 Claims. (Cl. 160—369)

This invention relates in general to a novel and an improved combination of a window frame and a window screen. More particularly, the invention contemplates extruded metal window frames and screens having extruded metal frames, and the invention is especially adaptable to so-called "Project-In" windows.

A primary object of the invention is to provide such a combination wherein means are provided for releasably or separably supporting a window screen in position on a window frame so that both inward and upward pressures are exerted on the screen frame to maintain the screen frame in tight abutting insect-excluding contact with the window frame and, at the same time, to firmly hold the screen frame in position with a minimum possibility of accidental displacement or rattling thereof.

Another object is to provide a combination of a window frame and a screen frame wherein the two frames have novel and improved yieldingly separably co-acting parts for mounting and holding the screen frame in the window frame and for permitting easy and quick application and removal of the screen frame to and from the window frame, respectively.

Still another object is to provide such a combination wherein the upper rails of the screen frame and the window frame shall have releasable interlocking parts; and the lower rail of the screen frame shall have spring clips to both hold the said interlocking parts of the screen frame and the window frame in interlocked position and, at the same time, to separably co-act with the window frame to releasably interlock the lower portion of the screen frame with the window frame.

Further, objects are to provide a simple, reliable and durable construction which can be economically manufactured; and to obtain other advantages and results that will be brought out by the following suggesting description in conjunction with the accompanying drawings in which:

FIGURE 1 is a front elevational view of a screen frame mounted in a window frame in accordance with the invention.

FIGURE 2 is detached rear elevational view of the screen.

FIGURE 3 is a greatly and enlarged fragmentary vertical sectional view on the plane of the line 3—3 of FIG. 1.

FIGURE 4 is an enlarged horizontal section view on the plane of the line 4—4 of FIG. 1.

FIGURE 5 is an enlarged fragmentary view of the portion on the top rail of the screen frame and the cooperating portion of the window frame as shown in FIG. 3.

FIGURE 6 is a detached perspective view of one of the spring clips.

Specially describing the illustrated embodiment of the invention the reference character A designates a window frame of generally known construction which in the present instance is an extruded metal frame mounted in a window opening B in a building wall C is known manner. Within the window frame is mounted a sash of any suitable construction which in the present instance is shown as comprising an extruded metal frame D in which is mounted a pane of glass E.

The sash D is mounted in a window opening F in the frame that extends through the front wall 1 of the window frame, the opening having an upper rail or lintel portion 2, a lower rail or sill portion 3 and side jamb portions 4.

2

The front wall 1 of the window frame A is common to both the upper and lower portion, and preferably smooth and flat, and in accordance with the invention the frame of a screen G is separably mounted on the window frame 5 in tight insect-excluding contact with said front surface of the window frame.

As shown, the screen G is rectangular and of a size such that the upper rail 5 abuts the upper rail or lintel 2 of the window frame within the window opening while the lower rail 6 abuts the front face of the lower rail or sill of the window frame below the lower edge of the window opening when the screen is applied to the window frame. The stiles 7 of the screen frame connect the upper and lower rails 5 and 6 and are spaced apart a distance such as they 10 about the front faces of the jambs 4 of the window frame when the screen is installed. As usual, a rectangular piece of woven wire 8 is secured in the screen frame in known manner, the rails and stiles of the frame in the present instance having grooves 9 into which the edge portions 15 of the woven wire mesh are bent and held by spring split tubes 10. The screen frame has some inherent resiliency and is provided on the inner side of its upper rail with a handle loop 11.

As shown, the lintel of the window frame has an under- 25 cut rabbet 12 at its rear side that may be formed by an outwardly extending depending lip 1a, and the upper rail 5 of the screen frame has a flange 13 upstanding from its top side of a length about equal to the width of the window opening F and adapted to seat in said rabbet behind said lip. The front side of the flange 13 is inclined 30 upwardly and rearwardly as shown at 13a. The lower rail 6 of the screen frame has a plurality of spring clips H secured to its underside by suitable means such as rivets 15. To prevent rotation of the clips on the frame, the 35 clips have upstanding lugs or flanges 16 that are inserted in slots 17 in the rail 6. Each clip is shown as having main end portion that abuts the screen rail and through which the corresponding rivet passes, and an intermediate portion 19 disposed at right angles to portion 18. At 40 the end of intermediate portion 19 opposite the main portion 18, the clip has a U-shaped crimp 20 which faces upwardly or toward the main portion 18 and whose arms are spaced apart a distance slightly greater than the thickness of wall 1 of the window frame. The arm 21 of the 45 crimp 20 opposite the portion 19 merges into a curved portion 22 extending away from the portion 19 and merging into a toe portion 23 the outer extremity of which is bent upwardly at 24 and curved laterally at 25a. The clip is inherently resilient so that the toe portion 23 there- 50 of may swing relatively to the main portion 18 that is rigidly secured to screen frame and the arms of the crimp may embrace the wall 1 at the upper edge of a transverse opening 25 in the sill portion of the front wall of the window frame. The window frame also has a horizontal partition 27 extending inwardly or rearwardly of the front wall from said openings 25 as best shown in FIG. 3.

When it is desired to mount the screen in the window frame, a person standing inside the window will lift the screen through the window opening end-wise as is usually done when installing screens from the inside of a house. The screen then is turned into its upright position and inclined slightly outwardly, whereupon the clips H are inserted through their respective openings. The screen is then pulled toward the window frame with the toe portions of the clip resting upon the partition 27. Thereupon, the screen is pressed downwardly against the resiliency of the spring clips by gripping handle 11, and the flange is slipped behind the lip 1a to the rabbet 12 as shown in FIGS. 3 and 6 after which the screen is released. The spring clips then elevate the screen to firmly hold the flange 13 in the rabbet and cause the arm 21 of each clip to frictionally bear upon inner surface of the wall 1 of the

window frame as shown in FIG. 3. The curved portion 22 and the arm 21 of each clip, thus cooperate with the front wall 1 to draw the screen frame into tight abutting contact with the face of said front wall, and at the same time, the inclined surface 13a of the flange 13 engages the rear side of the lip 1a to force the upper portion of the screen frame into contact with the face of the window frame. The arms 21 and the curved portions 22 of the clips, and the flange 13 of the screen frame firmly hold the frame against accidental displacement and in tight insect-excluding contact with the portions of the window frame bordering the window opening.

The manner of removing the screen will be obvious, the screen frame simply being pushed downwardly, to disengage the flange 13 from the lip 1a so that the frame can be tilted outwardly about its bottom end, the clips yielding under the downward pressure and holding the frame against complete accidental detachment from the window frame, which will prevent the screen from accidentally falling. Then the screen is tilted outwardly and the clips are pulled outwardly through their respective openings 25, after which the screen can be pulled inwardly of the window opening and out of the window frame.

While I have shown and described a now preferred embodiment of the invention, it should be understood that this is primarily for the purpose of illustrating the principles of the invention and that the details of the construction of the combination window frame and screen can be modified and changed in the spirit and scope of the invention. For example, there may be two or more flanges or lugs corresponding to the flange 13, and there could be one or more clips H, depending upon the sizes of the screen and window frames and the constructions thereof.

One advantage of the present invention is that it provides a simple and inexpensive manner of attaching a window screen to a known type of metal window frame which has a so-called drip lip corresponding to the lip 1a and also has a plurality of drain holes corresponding to the openings 25. The screen has attached thereto as a part thereof all hardware necessary for attaching the screen to the window frame, and there is no necessity for drilling or otherwise modifying the extruded metal window frame for adding screws or other fasteners or hangers. Other window frames could be provided with rabbets 12 and openings 25 to cooperate with flanges or lugs 13 and clips H on the screen frame.

It will also be understood by those skilled in the art that while the invention has been specifically described in connection with a window screen having a frame in which is secured a sheet of wire mesh, the invention also contemplates other frames having materials other than wire mesh therein; in other words the invention could be embodied in storm sash when desired. To avoid circumlocution, the term screen in the appended claims is intended to include other types of window closing panels such as storm sash.

I claim:

1. The combination with a window frame that has a front wall with a flat front face, jambs, a lintel portion having an inwardly extending lip, and a sill portion having at least one opening extending through said front face, of a screen that has a frame including a top rail, a bottom rail and stiles abutting said face of the window frame, said top rail having a flange seated behind said lip on the

window frame and said bottom rail having at least one spring clip secured thereon and extending through said opening in the sill portion of the window frame, said clip abutting a portion of said window frame rearwardly of said front wall and exerting yielding pressure on said screen frame tending to move the screen in its own plane to hold said flange behind said lip, and said clip also having a portion yieldingly and separably interlocking with the wall of said opening in the sill portion of the window frame and drawing said screen frame into tight abutting contact with the face of the window frame.

2. The combination as defined in claim 1 wherein said clip comprises a strip of resilient metal secured at one end to said screen frame that has a U-shaped crimp intermediate its ends which yieldingly embraces said wall of the opening in the window frame and has a toe portion at its other end engaging said portion of the window frame rearwardly of said front wall.

3. The combination of a window frame and a screen frame wherein said window frame has two end portions and two side portions providing a front wall common to all of said end and side portions the front surface of which is in a flat plane, and said screen frame has two end rails and two side rails providing a rear surface common to all of said rails and stiles in a flat plane, one end portion of the window frame and one rail of the screen frame having separably interlocking parts and the other end portion of the window frame and the other end rail of the screen frame having separably interlocking parts holding said screen frame on said window frame with said rear surface of the screen frame abutting the front surface of the window frame, said parts that are carried by the window frame having surfaces disposed rearwardly of said common plane of the said front wall to coact with surfaces of at least one of the parts on the second-mentioned end portion of the window frame and of the part on the second-mentioned rail of the sash frame coacting to yieldingly bias the screen frame in its own plane to hold the parts on the screen frame in interlocked relation to the parts on the window frame, the first-mentioned interlocking parts comprising a rabbet in the window frame and a flange on the end rail of the screen frame to be seated in said rabbet and the second-mentioned separably interlocking parts comprising the wall of an opening in the front wall of the window frame and a spring clip on the end rail of the screen frame projecting rearwardly beyond said rear surface of the screen frame to be inserted through said opening and having a portion to yieldingly embrace said wall and another portion to abut a part of said frame rearwardly of said front wall of the window frame and yieldingly bias the screen in its own plane to hold said flange seated in said rabbet.
